OF NEW YORK.

TORPEDO-GYROSCOPE.

1,312,084.

Specification of Letters Patent.

Patented Aug. 5, 1919.

Application filed October 25, 1915. Serial No. 57,815.

To all whom it may concern:

Be it known that we, ELMER A. SPERRY, a citizen of the United States of America, and Dr. ELEMER MEITNER, a subject of the King 5 of Hungary, residing at Brooklyn, New York, have invented new and useful Improvements in Torpedo-Gyroscopes, of which the following is a specification.

This invention relates to gyroscopic steering gear for torpedoes. The principal objects are to improve upon the type of gyroscopic apparatus which forms the subject matter of the copending application of Elmer A. Sperry for gyroscopic apparatus for torpedoes, filed August 26, 1915, Ser. No. 47,550, and to improve upon certain details of the form of spinning up device now employed.

Referring to the drawings which illustrate what I now consider to be the preferred form 20 of our invention:

Figure 1 is an elevation, partly in section, of a gyroscopic unit.

Fig. 2 is a plan view of a plate used as a terminal for the electric wires. Line 1—1 indicates the section plane of this plate shown in Fig. 1.

Fig. 3 is a corresponding view of a plate used in conjunction with the aforesaid plate.

Fig. 4 is an end elevation of the gyroscopic 30 unit on a reduced scale, the casing being omitted.

Fig. 5 is a detail of tops of the plates mentioned above.

Fig. 6 is a detail.

Fig. 7 is a bottom view of a clamping ring used to retain the gyroscopic unit in place.

More specifically, 1 and 2 denote a pair of electrically driven gyroscopes which are designed according to the general principles 40 outlined in said copending application.

Each gyroscope comprises a rotor 3 mounted on a spinning axis 4 in a frame or gimbal ring 5, which in turn is pivotally mounted in a vertical ring 6 on an axis 7, preferably 45 perpendicular to the spinning axis. Ring 6 is used to support both gyroscopes and is rotatably mounted about a vertical axis 8, 9 in the outer frame 15. The rings 5, 5 are geared together or otherwise connected so 50 that oscillations about axes 7 is prevented except in opposite directions. Gears 100 and 101 may be used for this purpose.

Either direct or alternating current may be used for driving the rotors, but preferably

I employ three-phase alternating current for 55 this purpose. The windings are placed entirely on the stator 10 which is mounted on shaft 4 as by means of ball bearings, 11. A difficult problem was presented to lead in current to the gyros without causing friction or other retarding forces about the vertical or horizontal axis. If slip rings are used, friction about the vertical axis is necessarily caused, while if flexible wires are dropped from a fixed part to the gyroscopes, 60 some force will be exerted in every position of the wires except their normal or vertical position. If the torpedo is fired upon a straight course, no difficulty is presented with the last mentioned arrangement, but if 70 the torpedo is fired at an angle, as is now frequently done, the wires, if hung vertically when the torpedo is started, would be twisted through a large angle after the torpedo had straightened upon its course. 75 The result would be that a torque would be exerted about the vertical axis of the gyroscope during the greater part of the run, since the gyroscope, of course, would not turn with the torpedo but would remain 80 fixed in space.

For overcoming the above mentioned difficulty, we suspend the leading-in wires 12 from a part of a plate 13 which is rotatably mounted on an axis in line with the vertical 85 axis 8—9 of the gyroscopic apparatus, our idea being to turn this plate through the angle that the torpedo is to traverse so that after the angle has been traversed the wires will hang vertically. Annular ring 14, fixed 90 to the main frame 15 which supports the gyroscopic apparatus is used to furnish a bearing for the plate 13 as indicated at 16. A spring finger 90 may be provided on frame 15 for engaging plate 13 to prevent 95 too free rotation thereof. The wires preferably droop from plate 13 through a guiding tube 17. Plate 13 is provided with a plurality of spring contact studs 18 to each of which one of the wires 19, which are combined to form wires 12, are connected. Studs 18 are adapted to engage sockets 20 in a second plate 21 which are preferably elongated for a purpose described hereinafter. Some of said sockets are insulated from the 100 plate and are connected to leading-in wires 122 so that current is introduced to the gyroscopes through sockets 20, studs 18 and wires 105

19. Plate 21 is also rotatably mounted about said vertical axis and is provided with a worm gear 22 with which a worm 23 meshes. Plates 13 and 21 are also connected by a stud 24 on plate 13 which extends through an aperture which is preferably in the form of a slot 25 in plate 21. To prevent relative movement between plates 21 and 13, under ordinary conditions, a plate 10 80 may be provided on plate 21 (Figs. 5 and 6), which has a hole or counterbore 81 for engaging over stud 24 so as to prevent said movement. Plate 80 is not secured to plate 21, however, but is pressed firmly thereagainst by a member 82 riveted or otherwise fastened to plate 21. Pins 83 on said member extend through an elongated slot 84 in plate 80 so as to limit and guide its movement. Spring washers 85 may be provided 15 so that plate 80 may slip on plate 21, if a considerable force is exerted thereon. Stop pins 86 on a fixed portion 87 of the torpedo are arranged to strike plate 80 if plate 21 is rotated by worm 23 through more than a predetermined angle, so as to prevent further movement of plate 81, thereby preventing the turning of plate 13 through a greater angle than is permitted by the construction of the gyroscopes. The apparatus is preferably so designed that the two plates 21 and 13 will turn together through all of the ordinary angles of fire, so that, if desired, the connection between them could be made rigid, but we prefer to provide the safety or lost motion means described, or its equivalent, to prevent possible damage to the apparatus in case the plate 21 should be turned through a larger angle than usual.
- The length of slots 25 and 84 are designed 40 with reference to the maximum angle through which the torpedo is designed to be turned. For this reason also sockets 20 are elongated so that studs 18 will have sufficient play to turn without interrupting the electrical contact.
- Preferably wires 12 are carried to an extension 24' on the vertical ring 6 and from thence are drooped so as to enter the motor through the spinning axis as shown. The wires are preferably drooped symmetrically from each side of frame 6 as illustrated in Fig. 4 so that no torque can possibly be exerted about the vertical axis. The entire gyroscopic unit, comprising all parts within or attached to frame 15, is readily removable from the torpedo, so that it may be stored separately and only placed in the torpedo shortly before the launching. For withdrawing the unit, the locking bolts 52 and driving gears 36, 39 and 140 hereinafter described should of course be first withdrawn. Then, upon loosening clamp screws 91, and giving the clamp ring 92 a quarter turn so as to bring the lugs 93 thereon into register with the opening spaces between lugs 94 on the main frame 95, the unit may be withdrawn. To place the unit within the torpedo, the operations just described are reversed. It should be noted that, according to our invention, no electrical connections need be made within the torpedo but that all contacts are made automatically on thrusting the gyroscopic unit within the torpedo through studs 18 and sockets 20.
- We prefer to provide each gyroscope with a latitude weight 125 which is secured to frame 5. These weights are symmetrically located on opposite sides of the vertical axis 8-9 in order that no torque should be exerted about the vertical axis in case the gyroscopes are tilted at an angle to the vertical. It will readily be seen that if both weights were located on the same side of the axis or if only one weight were employed that in launching, when the torpedo is not horizontal, a torque would be exerted about the vertical axis which would disturb the equilibrium of the gyroscopes.
- For spinning the gyros either electrical means may be employed, or an auxiliary compressed air starting means may be employed similar to that now used for such purpose. As explained in the co-pending application mentioned above, we have considerably improved and modified this construction, however, to adapt it for the special conditions imposed by employing a plurality of electrically-driven gyroscopes. Compressed air is admitted through pipe 30 and discharges through nozzle 31 on a turbine or impulse wheel 32 in the usual manner. Said wheel is mounted on shaft 33 which is rotatably supported in a sleeve 34 and which carries a worm 35. Also mounted on shaft 33 is a pinion 36 adapted to mesh with a gear 37 on rotor 3 of gyroscope 1. A bracket 38 secured to sleeve 34 supports a pair of gears 39, 140 which connect gear 37 with a similar gear 40 on rotor 3 of gyroscope 2, so that the two rotors are driven in opposite directions by the same spinning motor. A worm wheel 41 meshes with worm 35 and carries a pin 42 adapted to strike a trip 43 which in the present embodiment assumes the form of a bell crank lever pivoted at 44. Said trip normally engages an extension 45 on arm 46 which is secured to shaft 47. Arm 46 is provided with a notch which engages a projection 48 on sleeve 34 so that when trip 43 is moved by pin 42 arm 46 will suddenly draw sleeve 34 to the left through the action of the strong tension spring 50. This action it will be seen will withdraw all of gears 36, 39 and 140 from engagement with the pinions on the two rotors. While the above described throw-out mechanism may be used to release also the usual locking bolts which are used to hold the gyroscopes in place during the spinning up operation,

we prefer to employ a separate throw-out mechanism for the locking bolts. The two locking bolts, according to my invention, are mounted on a common frame 51 and 5 may be made in the form of sockets 52 adapted to engage the ends 66 of shafts 4. Secured to frame 51 is a slidably mounted shaft 54 to which is connected a bell crank lever 55. A strong spring 56 normally tends to draw said shaft to the left 10 but a catch 57 which engages extension 58 of lever 55 serves to hold the shaft 54 to the right, thus maintaining spring 56 under tension and the locking bolts 52, 53 in the 15 locked position. Catch 57 is designed to be operated upon some predetermined event, preferably upon the torpedo's being discharged from the torpedo tube, the end of lever 57 striking against a projection in the 20 tube (not shown) in the well known manner.

In addition to the locking bolts, we prefer to employ an auxiliary device for the purpose of damping out any oscillations that might be caused by or exist upon the 25 sudden release of the locking bolt. We have found by painstaking experiments that even when the driving gears are withdrawn from the gyro pinions before the release of the locking bolts, that minute oscillations 30 are set up by the said lock, which upon the release of the lock cause serious disturbance of the gyroscope. Our damping means is shown as a plate 60 slidably mounted on the rod 61 which contains socket 52. Guiding rods 62 may be attached to the plate, the rods extending through a guide 63 on rod 61. Rods 62 may be formed of one 35 piece of wire, so that the connecting portion 64 will form a stop adapted to limit the outward movement of the plate. A spring 65 normally forces the plate outwardly and into engagement with some portion of the gyroscope, preferably an extension 53 on ring 5 surrounding bolt 66. A ring 67 of 40 soft, vibration-absorbing material may be placed between plate 60 and extension 53. The plane of engagement between said parts should be parallel with axis 7, or, in other words, perpendicular to spinning axis 4, 45 so that by no possibility can a torque be exerted about axis 7 by the withdrawal of plate 60. It will be also readily appreciated that our auxiliary locking means will quickly damp out any oscillations that may 50 exist upon the release of lock 52, 66. The parts are so designed that stop 64 will withdraw plate 60 clear of the gyroscope so as to allow the gyroscopic apparatus three degrees of freedom during the run.

60 The operation of our invention is as follows:—After the unit is placed within the torpedo, as described above, the initial spin may be imparted to the gyroscopes either through our air starting means or electrically, as explained in the aforesaid applica-

tion for Letters Patent. We prefer to employ the locking bolts or their equivalent, no matter which way the gyros are started, since, even when starting the gyros electrically, means should be provided to position 70 them properly and to prevent wandering before their normal speed has been attained. By employing a separate throw-out mechanism for the locking bolts, we render it unnecessary to bring the gears on bracket 38 75 into mesh with pinions 37 and 40.

Prior to or during the spinning-up operation, the torpedo may be set for angle firing by rotating worm 23, thereby turning plate 21 through the predetermined angle. The 80 means whereby the turning of said plate accomplishes the result stated forms no part of the present invention and hence is not described in detail. A pair of sensitive fingers or feelers 96, 97 are carried by an extension 85 98 attached to plate 21, which contact with the stepped periphery 99 of a member 102 secured to the vertical ring 6, so that by turning plate 21, the fingers are shifted away from their normal position to a point 90 where they will actuate the rudder so that the torpedo will be turned until the fingers are again brought back to their normal position. The above-described turning of plate 21 will also result in the turning of plate 13 and the leading-in wires 12 through substantially the same angle (see dotted lines Fig. 4) so that when the torpedo has traversed the said angle or, in other words, has straightened upon its course, the wires 95 100 will be in their normal or vertical position. If the air starting means is used, the gears 36, 39 and 140 will be thrown out after a given number of revolutions by trip 43, and the locking bolts will be withdrawn upon 105 the launching of the torpedo.

In accordance with the provisions of the patent statutes, we have herein described the principle of operation of our invention, together with the apparatus which we now 110 consider to represent the best embodiment thereof, but we desire to have it understood that the apparatus shown is only illustrative and that the invention can be carried out by other means. Also, while it is designed to 115 use the various features and elements in the combination and relations described, some of these may be altered and others omitted without interfering with the more general results outlined, and the invention extends 120 to such use.

Having described our invention, what we claim and desire to secure by Letters Patent is:

1. In a torpedo, adapted for angle firing, 125 an electrically driven gyroscope pivotally mounted about a vertical axis, a rotatably mounted suspension element, a wire suspended from said element and connected with the gyroscope, and means whereby said 130

element may be initially turned so that said wire will hang substantially vertically when the torpedo straightens upon its course.

2. In a torpedo adapted for angle firing, 5 an electrically driven gyroscope, a wire support, flexible wires connecting said support and said gyroscope and means whereby said support may be set so as to bring the wires in their normal or natural position after said 10 angle has been traversed.

3. In a torpedo, a detachable, electrically driven gyroscope, and electrical contacts on 15 said gyroscope and within the torpedo adapted to complete automatically a circuit within the torpedo on placing the gyroscope within the torpedo.

4. In a torpedo, an electrically driven gyroscope, comprising an outer gimbal ring pivotally mounted about a vertical axis and 20 leading in wires drooped from a relatively stationary part to said gimbal ring.

5. In a torpedo, an electrically driven gyroscope, comprising an outer gimbal ring pivotally mounted about a vertical axis and 25 leading in wires drooped from a relatively stationary part to said gimbal ring and from thence within the gyro proper through the spinning axis.

6. In a torpedo, an electrically driven gyroscope, comprising an outer gimbal ring pivotally mounted about a vertical axis, a 30 rotatable support and leading in wires drooped from said support to said gimbal ring whereby said support may be set so that 35 the wires will droop substantially vertically from it after said angle has been traversed.

7. In a torpedo, gyroscopic apparatus comprising a pair of rotors, bearing frames for said rotors, a support for the frames to 40 which the frames are independently pivoted, and an eccentric latitude weight on each frame on opposite sides of the pivotal axis of said frames.

8. In a torpedo, gyroscopic apparatus 45 comprising a pair of rotors, bearing frames for said rotors, a support for the frames to which the frames are independently pivoted, said support being swiveled about a vertical axis, and an eccentric latitude 50 weight on each frame on opposite sides of said vertical axis.

9. In a torpedo, the combination with a 55 pair of gyroscopes, of a spinning up mechanism therefor comprising gears on the gyroscopes, a motor, gears for interconnecting said gyro-gears and motor and means whereby said last named gears may be withdrawn from engagement with said gyro gears.

60 10. In a torpedo the combination with a pair of gyroscopes, of a spinning up mechanism therefor comprising gears on the gyroscopes, a motor, gears for interconnecting said gyro-gears and motor whereby the 65 gyroscopes are rotated in opposite direc-

tions and means whereby said last named gears may be withdrawn from engagement with said gyro gears.

11. In a torpedo, the combination with a 70 pair of gyroscopes of a spinning up mechanism therefor comprising gears on the gyroscopes, a motor, gears for interconnecting said gyro-gears and motor, means for locking the gyros in a fixed position and means whereby said last named gears and lock may 75 be withdrawn from engagement with said gyro gears.

12. The combination with a torpedo, of a 80 detachable gyroscopic unit comprising an electro-motor gyroscope, an outer frame therefor, an electric contact mounted thereon and a coöperating contact mounted with- in the torpedo.

13. The combination with a torpedo hav- 85 ing a rotatable member adapted to be set for angle firing, of a detachable gyroscopic unit comprising an electro-motor gyroscope, and electrical conducting means leading through said rotatable member to the gyroscopic unit including a flexible wire and de- 90 tachable contacts.

14. The combination with a torpedo hav- 95 ing a rotatable member adapted to be set for angle firing, of a detachable gyroscopic unit comprising an electro-motor gyroscope, an outer frame therefor, a rotatable plate mounted on said frame, contacts borne re- 100 spectively by said member and plate and adapted to engage when the unit is placed within the torpedo, and a wire drooped from said plate to the gyroscope.

15. The combination with a torpedo hav- 105 ing a rotatable member adapted to be set for angle firing, of an electro-motor gyro- scope, and electrical conducting means leading through said rotatable member to the gyroscope including a flexible wire.

16. A detachable gyroscopic unit for tor- 110 pedoes comprising an outer frame, an elec- trically driven gyroscope pivotally mount- ed therein, for rotation about a vertical axis, a member also rotatably mounted on said frame and a flexible wire connecting said member and the gyroscope.

17. The combination with a dirigible de- 115 vice, of an induction electro-motor gyro- scope comprising a vertical ring, a rotor bearing frame pivotally mounted therein on a horizontal axis, a stator having windings mounted therein, a rotor for said stator 120 without the same and spinning about an axis at an angle to said other axis, and con- ducting elements leading into the stator along the last named axis.

18. The combination with a dirigible de- 125 vice, of an induction electro-motor gyro- scope comprising a vertical ring, a rotor bearing frame pivotally mounted therein on a horizontal axis, a stator having windings mounted therein, a shaft for supporting 130

4
said stator windings extending across said frame at an angle to said horizontal axis, a rotor journaled upon said shaft for said stator and inclosing the same, and conducting elements attached to said vertical ring and leading from there within the stator through said shaft.

19. The combination with a torpedo having a rotatable member adapted to be set for angle firing, of a detachable gyroscopic unit comprising an electro-motor gyroscope, an outer frame therefor, a rotatable plate mounted on said frame, contacts borne respectively by said member and plate and adapted to engage when the unit is placed within the torpedo, detachable means for causing said plate to turn with said member, and a wire drooped from said plate to the gyroscope.
20. In a spinning up mechanism for torpedo gyroscopes, a driving motor, a gyroscope, gears connecting said motor and said gyroscope, locking means for holding the gyroscope in a fixed position, and independent means for disconnecting said gears and for throwing out said locking means.

21. In a spinning up mechanism for torpedo gyroscopes, a driving motor, a gyroscope, gears connecting said motor and said gyroscope, locking means for holding the gyroscope in a fixed position, means for disconnecting said gears upon a predetermined event and independent means for throwing out said locking means upon the launching of the torpedo.

22. In a spinning up mechanism for torpedo gyroscopes, a driving motor, a gyroscope, gears connecting said motor and said gyroscope, locking means for holding the gyroscope in a fixed position, means responsive to the number of revolutions imparted to the gyroscope for disconnecting said gears and independent means for throwing out said locking means upon the launching of the torpedo.

23. The combination with a torpedo gyroscope of a locking mechanism therefor comprising a locking bolt adapted to hold the gyro axis in a fixed position, trip mechanism

for throwing out the bolt and yielding means for maintaining the position of the gyro axis during the tripping operation.

24. In a spinning up mechanism for torpedo gyroscopes, a driving motor, a gyroscope, gears connecting said motor and said gyroscope, locking means for holding the gyroscope in a fixed position, tripping mechanism for throwing out said gears and said locking means and yielding means for maintaining the position of the gyro axis until after the gears are disengaged.

25. In a spinning up mechanism for torpedo gyroscopes, a driving motor, a gyroscope, gears connecting said motor and said gyroscope, locking means for holding the gyroscope in a fixed position, tripping mechanism for throwing out said gears and said locking means and yielding means for maintaining the position of the gyro axis until after the gears and locking means are disengaged.

26. The combination with a torpedo gyroscope, of a locking and unlocking mechanism therefor comprising a positive locking device and an auxiliary means for damping out vibrations after the release of said positive device.

27. In a torpedo, a gyroscope supported for oscillation about an axis perpendicular to its spinning axis, a releasable locking bolt for preventing oscillation about said axis and a yielding means adapted to exert pressure on said gyroscope during the release of the bolt.

28. The combination with a torpedo having a rotatable member adapted to be set for angle firing, of an electro-motor gyroscope comprising a fixed frame, a gyroscopic element journaled therein for rotation about a vertical axis, a member rotatably mounted thereon, a guide-tube carried thereby for a flexible wire, and means for detachably locking said two rotatable members together.

In testimony whereof we have signed our names to this specification this twenty-third day of October, 1915.

ELMER A. SPERRY.
ELMER MEITNER.
